UNITED STATES PATENT OFFICE.

FREDERICK S. PINKUS, OF NEW YORK, N. Y.

DESIGN FOR CLOTH.

SPECIFICATION forming part of Design No. 16,532, dated February 16, 1886.

Application filed May 26, 1885. Serial No. 166,794. Term of patent 7 years.

To all whom it may concern:

Be it known that I, FREDERICK S. PINKUS, a citizen of the United States, residing in the city, county, and State of New York, have invented a new and original Design for Cloths, of which the following is a specification.

The main part of the design, which is intended for table-cloths, consists of a block of squares repeated throughout the fabric, and in connection with this it consists of a border, striped or checkered, as shown in the accompanying drawing.

The squares are shown in this drawing at A B C D. The square A is without stripes throughout. The square B, bounded by lines 1 1 1 1, is composed of stripes. The square C is plain throughout. The square D, bounded by lines 1 2 2 2, is composed of stripes continuous with the stripes of the square B. In line with the plain squares A and C, and extending to the edge of the cloth, is a row of

transverse stripes, $h h' h' k h' k$. In line with the squares B and D, and extending to the edge of the cloth, is a second row of transverse stripes, being a continuation of the transverse stripes $h h' h' k h' k$. The stripes of the squares B and D are extended across the transverse stripes of the second row. 25

I claim as my invention—

The design consisting of the plain squares A C and squares B D, made up of stripes, and the border consisting of rows of transverse stripes h , g , h' , and k , crossing blocks and stripes of the fabric, substantially as described and shown. 30

In testimony whereof I have signed my name to this specification in the presence of two subscribing witnesses.

FREDERICK S. PINKUS.

Witnesses:

WM. C. PHILLIPS,
L. WÜSTEFELD.
